UNITED STATES PATENT OFFICE.

BASIL W. HENDRICKS, OF BARRY, ILLINOIS.

GASOLENE-ENGINE.

1,359,890.

Specification of Letters Patent. Patented Nov. 23, 1920.

Application filed March 1, 1918. Serial No. 219,939.

To all whom it may concern:

Be it known that I, BASIL W. HENDRICKS, a citizen of the United States, residing at Barry, in the county of Pike and State of Illinois, have invented certain new and useful Improvements in Gasolene-Engines; and I do hereby declare the following to be a full, clear, and exact description of the invention, such as will enable others skilled in the art to which it appertains to make and use the same.

This invention relates to improvements in internal combustion engines, and has for one of its objects the provision of a device of this character, which shall be simple, durable and efficient, and which may be manufactured and sold at a comparatively low cost.

Another object of this invention is the provision of an overhead valve construction which is capable of producing more power on a less amount of fuel over that of other engines and which will produce an even running engine.

With these and other objects in view as will become more apparent as the description proceeds, the invention consists in certain novel features of construction, combination, and arrangement of parts as will be hereinafter more fully described and claimed.

For a complete understanding of my invention reference is to be had to the following description and accompanying drawings, in which:—

Fig. 1 is a plan view of an engine constructed in accordance with my invention,

Fig. 2 is a side elevation of the same with one of the fly wheels removed,

Fig. 3 is a longitudinal sectional view illustrating the construction of the piston,

Fig. 4 is a fragmentary sectional view of the overhead valve construction,

Fig. 5 is a plan view of the same illustrating the valve cage,

Fig. 6 is a detail sectional view of a make and break mechanism for the ignition system.

Referring in detail to the drawings, the numeral 1 indicates a base having mounted thereon a horizontal cylinder 2 in which is reciprocally mounted a piston 3. The piston 3 has connected thereto by means of a wrist pin 4, the usual connecting rod 5. A crank shaft 6 is journaled in the base 1 and has connected thereto the connecting rod 5

and has mounted upon each end the usual fly wheel 7. The piston 3 is provided with a plurality of openings or apertures 8 for the purpose of reducing the weight of the same. The piston 3 is lubricated within the cylinder 2 by means of a pipe 9 carrying an oil cup 10. The cylinder 2 has formed thereon an annular flange 11 which is adapted to support an ordinary water jacket about the cylinder 2 for the purpose of cooling the cylinder and piston and which water jacket is not shown. A removable head 12 is secured to the cylinder 2 by means of bolts or like fasteners 13 and has a recess or socket 14 in which is positioned a valve cage 15. The removable head 12 has an intake port 16 and an oppositely disposed exhaust port 17. The valve cage 15 is provided with ports that communicate with the intake and exhaust ports 16 and 17 of the valve head. A suitable exhaust pipe 18 is secured within the exhaust port 17 of the head while the manifold 19 is secured within the intake port 16. The valve cage 15 has formed therein intake and exhaust valve seats 20 which receive intake and exhaust valves 21. The stems of the valves 21 are slidably mounted in guides 22 which are threaded into openings in the head 12 permitting the stems to extend through the head. The valve stem of the intake valve 21 has mounted thereon a spring 23 for normally holding the same in a seated position. The stem of the exhaust valve 21 is provided with a spring 24 for the purpose of holding the same in a seated position. A standard 25 is secured to the head 12 and has pivoted thereto a rocker arm 26. The rocker arm 26 has an adjusting bolt 27 carried by one end which is adapted to engage the outer end of the valve stem of the exhaust valve. An actuating rod 28 is pivoted to the other end of the rocker arm 26 and is slidably mounted in the base 1 and carrying at its other end a roller 29 adapted to engage a cam 30. An arm 31 is pivoted to the base 1 as illustrated at 32 and to the actuating rod 28 adjacent the roller 29 for the purpose of supporting said rod in engagement with the cam 30. The cam 30 is carried by a countershaft 33 journaled in the base and driven by a gear 34 that meshes with a gear 35 secured to the crank shaft 6. The gears 34 and 35 are known as the timing gears and which are of such a ratio that they will open the exhaust valve to permit the escape of

- the burnt charge in the cylinder 2 upon the scavenging stroke of the piston 3. The cam 33 is adapted to actuate the actuating rod 28 to rock the arm 26 upon its pivot to unseat 5 the exhaust valve. A spring 36 is secured to one end of the rocker arm 26 and to the head 12 for the purpose of holding the roller 29 in engagement with the cam 33 at all times.
- 10 The head 12 is provided with a threaded opening to receive a spark plug 37 and the valve cage 15 has a recess 38 which communicates with the spark plug opening of the head 12 so that when the spark occurs 15 between the electrodes of the spark plug, the fuel within the cylinder 2 will be ignited. An oscillating member 39 is mounted for movement about the counter-shaft 33 and is of substantially arcuate shape having 20 connected to one end a rod 40 which is in turn connected to a controlling lever 41. The controlling lever 41 is mounted upon a pivot 42 carried by the base 1 whereby upon 25 rocking the lever 41 upon its pivot the position of the member 39 can be varied about the counter-shaft. A tension means 43 is carried by the pivot 42 so that the controlling lever 41 will be held against accidental movement. A contact 44 is carried by the 30 member 39 and is insulated therefrom by means of a suitable insulating material 45 and is adapted to coöperate with a spring contact 46 carried by the member 39 and which is engaged by a cam 47 carried by the 35 counter-shaft 33 for moving the same into engagement with the contact 44 to complete an electric circuit.
- Conductors 44' and 48 are connected to the contacts 44 and the spark plug 37 re- 40 spectively and to the primary and secondary of a coil (not shown). As soon as the electric circuit is completed to the spark plug, a spark is produced which ignites the fuel within the cylinder 2. By having the 45 member 39 movable about the counter-shaft 33 and controlled by the controlling lever 41 provides means whereby the sparks may be advanced and retarded as desired. The manifold 19 may have connected thereto 50 any desired type of fuel tank as illustrated

at 49 for the purpose of furnishing the manifold or carbureter 50 with explosive fuel, such as gasoline or the like.

In operation upon the suction stroke of the piston 3, the intake valve 21 is opened 55 permitting the fuel from the carbureter to enter the cylinder. The piston 3 then moves in the direction of the head 12 compressing the charge. When the charge has been compressed, the cam 47 moves the contact 46 in 60 engagement with the contact 44 completing an electric circuit to the spark plug thus exploding the charge within the cylinder 2 which forces the piston away from the head 12 driving the crank shaft. The cam 30 65 then moves the actuating rod 28 which rocks the arm 26 upon its pivot opening the exhaust valve permitting the burnt charge to escape through the exhaust pipe 18.

While I have shown and described the 70 preferred embodiment of my invention, it will be understood that minor changes in construction, combination and arrangement of parts may be made without departing from the spirit and scope of the invention, 75 as claimed.

Having thus described my invention, what I claim is:

An engine including a cylinder having a reciprocating piston, a removable head closing one end of the cylinder and having a recess communicating with the intake and exhaust ports, an igniter opening formed in said head, said igniter opening adapted to receive an igniter, a cage located in said 80 recess and having passages communicating with the intake and exhaust ports and the igniter opening, valve seats formed in a pair of the passages, sleeves threaded in the pair of passages and extending through one face 90 of the head, and self-closing valves in the passages engaging the valve seats and having their stems extending through the sleeves.

In testimony whereof I affix my signature 95 in presence of two witnesses.

BASIL W. HENDRICKS.
